PORTABLE SUPPORT

Earl H. Hurley, Emporium, Pa.

Application April 30, 1940, Serial No. 332,584

3 Claims. (Cl. 248—351)

This invention relates to an adjustable portable support designed primarily for use in supporting plumbing pipes, electric light fixtures or the like, the primary object of the invention being to provide means which may be readily and easily secured in position to support various types of articles, without the use of nails, bolts or the like.

An important object of the invention is to provide a device of this character which may be readily and easily adjusted, adapting it for use between walls or supporting beams of various widths.

A further object of the invention is to provide a support which when positioned, will be securely held in place, and cannot become displaced under the weight of the article supported thereby.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is an elevational view illustrating the support as placed between adjacent walls or supporting beams prior to the moving of the sections of the support to their active supporting positions.

Figure 2 is a longitudinal sectional view through the support, illustrating the support as positioned for supporting an object.

Figure 3 is a plan view of the support showing the sections thereof as in their extended positions.

Figure 4 is a sectional view taken on line 4—4 of Figure 3.

Figure 5 is a longitudinal sectional view through a modified form of the invention.

Figure 6 is a plan view thereof.

Figure 7 is a sectional view taken on line 7—7 of Figure 5.

Referring to the drawings in detail, the support comprises a pair of sections 5 and 6 constructed of channel bar material, the section 5 being wider than the section 6, so that the section 6 may fit within the section 5, and slide longitudinally thereof.

The outer ends of the sections 5 and 6 are constructed to provide prongs or piercing points

7, and shoulders 8 disposed directly above the prongs 7, the shoulders being designed to engage the surface of the beam or wall into which the prongs are forced, restricting movement of the prongs within the surface, and at the same time providing an exceptionally rigid support.

The section 6 is formed with a plurality of spaced notches 9 formed with offset portions 10, which are disposed in the bottom thereof. 10 The section 6 is also formed with a downwardly extended spring tongue 11 which is comparatively long and formed with inclined portions adapted to engage the edges of the cut-out portions 12 of the section 5, securely locking the sections 5 and 6 together.

The inner end of the section 5 is formed into a tongue 13 that extends upwardly, the tongue being of a width to fit within the offset portion 10 of the section 6, with which it is used.

20 This tongue 13 is also formed with an enlarged end portion 14 spaced from the bottom of the section 5, a distance to provide a clearance for the bottom of the section 6, when the sections are moved together. Thus it will be seen that due to this construction, the sections 5 and 6, while they may be disconnected, are so arranged that they may be adjusted with respect to each other to adapt the support for use in connection with supporting surfaces various distances apart.

25 In the form of the invention as shown by sheet 2 of the drawings, the sections 15 and 16 are arranged to slide longitudinally with respect to each other, the section 15 being provided with longitudinal grooves 17 disposed on the inner sides of the flanges 18 of the sections, the grooves accommodating the enlargements 19 extending outwardly from the flanges 20 of the section 16.

30 A T-shaped tongue indicated at 21 is also formed at the inner end of the section 15, and extends into the openings 22 of the section 16. The openings 22 are also formed with offset portions 23, to receive the tongue 21, locking the sections against vertical movement in one direction, under ordinary conditions.

45 Prongs 24 are formed at the outer ends of the sections 15 and 16 and are adapted to be forced into the beams or surfaces between which the support is held. The shoulders 25 in this form of the invention provide stops to engage the supporting surfaces adjacent to the prongs, providing a rigid support.

50 From the foregoing it will be seen that due to the construction shown and described, I have provided a support which may be readily adjusted between two supporting surfaces and moved to its

active and supporting position, by moving the inner ends of the sections downwardly into direct alignment with each other, as shown by Figures 2 and 5 of the drawings.

It will also be noted that the device, may be used for supporting various types of articles, such as pipes, scaffolding, and by making the sections of light material, the support may be used in supporting poles or clothes hangers.

Since the shoulders adjacent to the prongs, 10 are disposed vertically, it will also be noted that these shoulders will bear against the surfaces between which the support is positioned, securely bracing the outer ends of the support to insure against accidental displacement of the support, 15 after it has been properly positioned.

What is claimed is:

1. A portable support comprising a pair of telescoping sections, one of said sections having notches formed with offset portions, the adjacent section having a tongue formed at its inner end, the tongue having an enlarged end portion, said tongue adapted to extend into the notches, and pass into the offset portions of the notches, securing the inner ends of the sections together, and 20 prongs formed at the free ends of the sections, the prongs adapted to be embedded in supporting surfaces with which the support is used.

2. A portable support comprising inner and outer sections, said sections having openings formed therein, a T-shaped tongue on the inner end of the outer section and being fitted in an opening of the inner section, pivotally connecting the sections, and a spring tongue formed at the inner end of the inner section and adapted to extend into an opening of the outer section, securing the sections in their extended positions, and spurs on the outer ends of said sections adapted to be embedded into a supporting surface.

3. A portable support comprising inner and outer sections constructed of channel bar material having their open sides disposed upwardly, each section having openings formed in the bottom thereof, the openings in the inner section having offset restricted portions, a spring tongue on the inner end of the inner section adapted to extend into openings in the outer section, a substantially T-shaped tongue extending upwardly from the inner end of the outer section, the T-shaped tongue adapted to move into the restricted portion of the openings formed in the inner section, frictionally engaging the bottom of the inner section adjacent to the opening.

EARL H. HURLEY.
